US00D660056S

(12) **United States Design Patent**
Diffrient

(10) **Patent No.:** **US D660,056 S**
(45) **Date of Patent:** **** May 22, 2012**

(54) **CHAIR**

(75) Inventor: **Niels Diffrient**, Ridgefield, CT (US)

(73) Assignee: **Humanscale Corporation**, New York,
NY (US)

(**) Term: **14 Years**

(21) Appl. No.: **29/406,826**

(22) Filed: **Nov. 18, 2011**

Related U.S. Application Data

(63) Continuation of application No. 11/425,298, filed on Jun. 20, 2006, now Pat. No. 8,061,775.

(51) **LOC (9) Cl.** **06-01**

(52) **U.S. Cl.** **D6/500; D6/366**

(58) **Field of Classification Search** D6/334–336,
D6/364, 365, 366, 367, 374, 375, 379, 500–502;
297/411.29, 411.35, 285, 340, 341, 300.1–300.5,
297/452.13, 452.29

See application file for complete search history.

(57) **CLAIM**

I claim the ornamental design for a chair, as shown and described.

DESCRIPTION

FIG. 1 is a front perspective view of a chair embodying the present invention;

FIG. 2 is a front view of the chair of FIG. 1;

FIG. 3 is a rear view of the chair of FIG. 1;

FIG. 4 is a right side view of the chair of FIG. 1;

FIG. 5 is a left side view of the chair of FIG. 1;

FIG. 6 is a top view of the chair of FIG. 1; and,

FIG. 7 is a bottom view of the chair of FIG. 1.

The broken lines shown herein, including the intersecting broken lines covering the chair back support surface and chair seat support surface, are for illustrative purposes only and form no part of the claimed design.

1 Claim, 7 Drawing Sheets
